UNITED STATES PATENT OFFICE

THOMAS J. J. WASLEY, OF SANTIAGO, CHILI, ASSIGNOR TO AUTOMOBILE PATENTS, INC., OF NEW YORK, N. Y.

CARBURETOR

Application filed July 13, 1928. Serial No. 292,359.

My present invention has for its object to provide a carburetor particularly adapted for use in conjunction with hydrocarbon engines which comprises few parts of simple construction so arranged that the required amount of fuel may be supplied to the air intake leading to the manifold of an engine of given horse-power rating and thoroughly mixed or commingled with the air to form a proper explosive mixture.

My invention further comprehends providing a carburetor which is especially adapted for use in carburizing so called low grade fuel oils and to this end contemplates a structure in which the fuel is introduced into the air stream under pressure in a finely comminuted state which at once facilitates its vaporization and render its admixture with the air stream complete as the air and vapor pass onward into the engine manifold.

To these and other ends the invention comprises further improvements all as will be further described in the following specification, the novel features being particularly pointed out in the appended claims.

In the drawings:

Figure 1, is a longitudinal sectional view of the carburetor illustrating one embodiment of my invention.

Figure 2, is a top plan view thereof.

Figure 3, is a plan view of the oil pressure cylinder and the surrounding air vanes.

Figure 4, is a cross sectional view taken on the line 4x4x of Figure 1.

Similar reference characters in the similar figures, indicate similar parts.

In a carburetor for hydrocarbon engines and particularly those designed for vaporizing the cheaper low grade fuels which it is essential to use where economy in the operation is sought in conjunction with engines of large horse-power operating at slow speed, it is desirable that the fuel shall be delivered to the air column passing to the engine manifold as nearly in the form of a vapor as it is possible to obtain immediately in the vicinity of its point of discharge. This is due somewhat to the necessary restrictions in the size of the air passage and also the measurable time which is required to permit com-

plete evaporation of the fuel and its commingling with the air currents to occur.

In carrying out my invention I have provided a carburetor comprising a shell or casing 1, forming an air intake passage. Removably secured to the forward end of the casing is a head or extension 2, which preferably opens at one side of the axis of the casing, the entrance thereto being, protected by the perforated cover 3, supporting a fine mesh screening. In the throat of the head is located the usual so-called butterfly valve or throttle 5. The throat formed in the head 2, beyond the throttle flares outwardly as indicated at 6, to the full diameter of the casing 1, to which it is secured by screw threads 7. Attached to the rear end of the casing is a tubular extension 8, which may be in the form of an elbow or otherwise shaped to form a convenient means of attaching the carburetor to the intake manifold 9, of a hydrocarbon engine as will be understood.

Located within the air passage and so arranged as to be preferably disposed entirely within the casing 1, is a centrally disposed tubular body 10, forming a fuel chamber to which liquid fuel is supplied under pressure in any suitable manner, as indicated by the pressure feed pipe 11. At its forward end the chamber 10 terminates in a nozzle 12 which points in the direction of the incoming current of air and terminates in a valve seat 13, the face of which is preferably conical and formed on an angle the plane of which, if continued, will, as indicated by the arrows in Figure 7, impinge against the inner flaring surface of the throat 6, of the air passage in the inlet head. Fitting within the nozzle 12 is a stem 14, carrying a valve head 15, which cooperates with the seat 13. These parts may, if desired, be connected to a common valve stem, the inner end of which, as indicated at 16, projects into the pressure chamber and is surrounded by a spring 17, which normally tends to hold the valve head retracted in the closed position. The other end of the valve stem, indicated by 18, is carried to a point exterior of the carburetor where it will be accessible for manual ma-

nipulation when it is desirable to unseat the valve head 15.

One of the essential features of my invention consists in the proper proportioning of the length of the nozzle 12, and the diameter of the nozzle and the exterior diameter of the stem 14, as I have discovered that by ejecting fluid under pressure through a passage of appreciable length and which is sufficiently restricted so that it may be caused to be emitted in a finely comminuted state.

It will be understood that if desired a carburetor such as I have shown may be designed to provide a vapor discharge of fuel oil constantly in a quantity properly regulated to the requirements which will produce the best efficiency in an engine of given size when the stem and valve head are adjusted only sufficiently to open the nozzle. 15 It will also be seen that if it is desired to increase the flow of fuel a further outward movement of the stem will uncover more of the nozzle in rear of the stem thus reducing the length and area of the narrow slit making it possible for the pressure in the chamber to expel a larger quantity of oil.

In practice I have discovered that the size of the slit between the interior bore of the nozzle and the surface of the enclosed stem 30 will depend upon the volatility of the fuel oil employed and the number of pounds pressure under which it is delivered to the pressure chamber. A thin fuel oil such as the lower grades of gasoline and kerosene may 35 be successfully vaporized by the use of a nozzle in which the outlet is $1\frac{1}{2}$ inches long and the clearance is as small as from four to eight thousandths of an inch (dependent somewhat upon the character of the workmanship). With heavier fuels the dimensions 40 may vary somewhat and while the length of the nozzle may remain the same the clearance should be slightly increased and in some instances may be as great as two thousandths 45 of an inch. The clearance allowed for the escape of the fuel oil should also be regulated with reference to the pressure used and this will be in most cases determined by special circumstances. In practice I have obtained 50 very satisfactory results with pressures as low as 75 and 100 pounds per square inch at the fluid chamber.

The fluid pressure chamber is disposed centrally in the air intake passage and it is 55 supported in this position by a series of surrounding radially extending diagonally disposed blades. There are preferably four spaced sets of these blades as indicated by 19, 20, 21 and 22, the alternate sets being arranged with their blades inclined in the same direction and these being arranged in rear of the nozzle (considered with reference to the direction of the flow of air through the intake) constitute a series of baffles which 60 assist in the vaporization of the fuel oil and 65

its comingling with the air currents to insure a very thorough carburization before the mixture reaches the intake manifold of the engine.

While I have shown the nozzle as having 70 a circular cross section, as I deem this form the more practical from the stand point of machine work, it will, of course, be understood that the cooperating elements may be otherwise constructed. For instance, the 75 nozzle may be flattened to provide a narrow slit of the proper length to cause the breaking up of the globules of the fuel oil and insure its emission in the desired comminuted condition. 80

I claim as my invention—

In a carburetor, the combination with an exterior casing forming an air passage, of an interior oil pressure chamber centrally disposed in said casing having an elongated nozzle of constant inner diameter extending in a direction toward the air intake and provided with a valve head, a stem of constant diameter closely fitting the nozzle with such small clearance to cause the emitted liquid fuel to be comminuted to an extremely fine degree of division, a valve head on the stem cooperating with the valve seat, a spring within the chamber actuating the stem in one direction to seat the valve head, and pressure means for moving the stem in the opposite direction. 90

In testimony whereof, I have affixed my signature to this specification.
